UNITED STATES PATENT OFFICE.

ARTHUR E. BOYCE, OF MONTEREY, CALIFORNIA.

BRICK-KILN.

1,041,006.

Specification of Letters Patent. Patented Oct. 15, 1912.

Application filed July 6, 1911. Serial No. 637,099.

To all whom it may concern:

Be it known that I, ARTHUR E. BOYCE, a citizen of the United States, residing at Monterey, in the county of Monterey and State of California, have invented certain new and useful Improvements in Brick-Kilns; and I do declare the following to be a full, clear, and exact description of the invention, such as will enable others skilled in the art to which it appertains to make and use the same.

This invention relates to improvements in kilns for burning bricks and other clay products, the apparatus being known as continuous burning kilns.

The principal object of the invention is to construct a kiln by means of which the bricks may be gradually heated to the maximum temperature required for their burning during their manufacture and gradual cooling without cracking or checking.

Another object is to provide devices which will utilize the maximum of heat contained in the fuel used and eliminate a large percentage of labor which is at present required in handling and rehandling the brick during the burning process.

Another object is to provide means for controlling at all times the heat used in the kiln and for uniformly distributing it to all parts of the bricks being kilned and keeping the bricks under observation during the process.

Another object is to provide means for drawing off the heat exuding from the cooling bricks and to utilize it for drying bricks made by the several mud processes or of such composition which require drying before being kilned.

Another object is to construct an apparatus in which the bricks are constantly retained on the cars from the time they leave the molds until the entire drying and burning processes are completed.

With these and other objects in view the invention consists of certain novel features of construction, combination and arrangement of parts as will be more fully described and particularly pointed out in the appended claim.

In the accompanying drawings: Figure 1 is a longitudinal vertical section of one end of this improved apparatus; Fig. 2 is a similar view of the other end; Fig. 3 is a horizontal section taken through the portion of the apparatus shown in Fig. 1; Fig.

4 is a similar view taken through the portion of the apparatus shown in Fig. 2; Fig. 5 is a vertical transverse section taken on the line 5—5 of Fig. 1; Fig. 6 is a similar view taken on the line 6—6 of Fig. 2; Fig. 7 is a horizontal section of the carrying car taken on the line 7—7 of Fig. 6; Fig. 8 is a vertical longitudinal section taken on the line 8—8 of Fig. 5 showing the vertical arrangement of the air passages.

In the embodiment illustrated two parallel laterally spaced chambers or tunnels 1 and 2 are shown constructed of any suitable fire resisting material preferably of a composition of concrete and fire-brick. These tunnels may be of any desired length and size to accommodate any desired number of cars and a transfer chamber 3 is arranged transversely across one end and communicates with both of said tunnels and in which cars from one tunnel are transferred to the other tunnel as will be hereinafter more fully described. These tunnels are provided with tracks as 4 on which the cars travel, said tracks being preferably mounted on a cement or other suitable foundation preferably constructed of supporting beams 5 and 6 having an air space 7 arranged between them to permit the passage of cool air 85 below the cars.

The bricks from the molds are loaded onto flat cars preferably constructed as shown with a fire clay composition 8 arranged over the top of each car to protect the car from the heat in the kiln during its passage therethrough and vertically spaced above this fire resisting platform or cover 8 is a horizontally disposed table or platform 9 composed of fire resisting material and having a multiplicity of openings as 10 therein to permit the passage of the heated air from the bricks supported thereon to the space or chamber formed between said platform and the upper face or floor 8 of the car. This table or brick supporting platform 9 is mounted or secured to fire resisting side members 11 and an intermediate member 12 as is clearly shown in Figs. 5 and 6. Depending from the sides of the car are continuous rails 13 and 14 which are luted in sand boxes as 15 secured to the side walls of the tunnel and which are designed to prevent the access of heat to the car and thereby prevent injury or warping of the car.

The passages or chambers formed between the vertically spaced platforms 8 and 9 are

provided with dampers as 16 which extend entirely across the passages and are adapted for changing at will the direction of the heat either up or down through the cars during their passage through the kiln. (See Fig. 8.) These dampers may be operated by any suitable means, either by hand before the car enters the kiln, or by means arranged within the kiln.

10 A plurality of furnaces as 17 are arranged adjacent the tunnels 1 and discharge their heat through passages 18 on the opposite sides of the tunnel being deflected upward by fire brick partitions 19 as shown clearly in Fig. 5. The heat so deflected passes to the top of the tunnel 1 and then downward through the brick 20 which is arranged on the platform 9 of the car with spaces 21 between them as shown clearly in the various 15 figures of the drawing, said brick being so arranged to permit the circulation of the heated air whereby it is brought into contact with the various bricks so arranged. The heat passing through the brick on the cars is deflected into the passage or chamber formed 20 between the tables 8 and 9 by the action of a damper 22 arranged transversely across the tunnel 1 and which is adapted to be raised or lowered as desired. Arrows are shown 25 in Fig. 1 illustrating the general direction of the heat current. When the damper 22 is raised a sufficient distance the heat passes from the chamber formed between the platforms of one car into the corresponding 30 chamber of an adjacent car and thence passes upward through the openings 10 in the platform 9 of said last mentioned car and through the brick mounted thereon to the flues 23 arranged above the opening 35 40 through the top of the tunnel and which are provided with dampers as 24 for regulating the draft thereof. This tunnel 1 is provided at its opposite ends with doors 25 and 26 and when it is desired to introduce a new 45 carload of brick into the kiln the doors 25 and 26 and the damper 22 are opened simultaneously and the car introduced through the opening 26 which forces the cars in front of it forward and discharges the car adjacent 50 the door 25 into the transfer chamber 3 and the doors 25 and 26 and damper 2 are again immediately closed.

The transfer chamber 3 has a track 27 extending longitudinally thereof and transversely across the ends of the tunnels 1 and 55 2 and a car 28 is designed to travel on this track 27 and is arranged to receive the car ejected through the door 25. When the car from the tunnel 1 has been forced onto the 60 car 28, said car 28 with its load is moved longitudinally in the transfer chamber preferably by a suitable pull exerted through an opening 29 at one end of the chamber 3.

When the car 28 has been brought into position opposite the tunnel 2, a tool inserted

through the opening 30 will force the car containing the brick from the transfer car 28 onto the tracks in the cooling chamber or tunnel 2. The insertion of the car at this end of the tunnel 2 forces a car out from the opposite end of the tunnel and the brick contained on the car so forced out is in condition to be removed and carted to a suitable place of deposit. The tunnel 2 forms the cooling chamber or tunnel wherein the heated product is gradually cooled thereby preventing cracking or checking of the brick.

The tunnel 31 is arranged parallel with the cooling tunnel 2 and preferably adjacent thereto being connected with said tunnel 2 preferably near its discharge end by means of a conduit 32 having a fan 33 arranged therein and which is designed to draw out the heated air which exudes from the cooling bricks and force it into the tunnel 31 which contains carloads of green brick to be dried before burning. A flue 34 having a regulating damper 35 arranged at the opposite end of the tunnel 31 draws the heated air forced in from tunnel 2 by fan 33 through the tunnel 31 to bring it in contact with the brick contained on the various cars arranged in the tunnel 31; and the heated air so drawn through tunnel 31 produces a drying effect on the green brick in tunnel 31 and prepares it for the burning tunnel 1. While the fan 33 is not in any way designed for a cooling element for the brick in tunnel 2, yet it produces a draft through said tunnel and thereby assists in the cooling of the brick. It is of course understood that the brick is not continually passing through these tunnels but remains therein for a greater or less time as may be required, gradually cooling in the tunnel 2 whereby checking of the surface is prevented. The brick cars in tunnel 31 may pass in either direction.

The tunnel 1 is provided in one or both of its sides with a plurality of openings 36 covered by any suitable transparent material and which are designed to enable the operator to inspect the brick during the burning process.

It will thus be obvious that the various tunnels are kept continuously supplied with cars loaded with brick in the various steps of being burned, the cars at the inner end of the tunnel 1 having been subjected for the longest period to the heat in the kiln, and as the car from this end of the tunnel is transferred to the cooling tunnel 2, a car is ejected from said tunnel 2 and another car is removed from the tunnel 31 and introduced through the door 36 into the tunnel 1 and this process may be continuously performed making substantially an endless chain.

From the foregoing description taken in connection with the accompanying drawings

the construction and operation of the invention will be readily understood without requiring a more extended explanation.

Various changes in the form, proportion and the minor details of construction may be resorted to without departing from the principle or sacrificing any of the advantages of the invention as defined in the appended claim.

0 I claim as my invention:

A brick kiln having a track extending therethrough, heat supplying means for said kiln, cars adapted to travel on said track and having a fire resisting platform ar-

ranged on the upper face thereof, and an 15 apertured fire resisting brick supporting table spaced above said platform, and a damper arranged in the space between said table and platform for controlling the direction of heat passing therethrough. 20

In testimony whereof I have hereunto set my hand in presence of two subscribing witnesses.

ARTHUR E. BOYCE.
